GARMENT GUARD

Leo Peters, Evanston, Ill.

Application April 22, 1949, Serial No. 89,115

10 Claims. (Cl. 20—16)

1

This invention relates to a garment guard and is particularly useful in the protecting of garments, and the like, which are suspended upon a door or other building panel for safekeeping until an authorized pick-up man takes away the garments for cleaning, and for further safeguarding the garments after they are returned by the deliveryman until the housewife returns home.

In accomplishing the safeguarding of clothes, and the like, either before they are picked up by the dry cleaner's representative or after the same have been delivered by him and prior to the return of the housewife, it is of the utmost importance that the means employed be of simple and inexpensive design and require as little change or alteration of the door or building structure as possible, while at the same time it is desirable that the structure interfere as little as possible with the vision through the door windows and be operable without requiring a key or other device upon the part of the housewife. At the same time, the structure must be accessible to the deliveryman, etc. through the use of a key or a known combination, if the lock is a combination lock, etc.

An object of the present invention is to provide a garment guard structure of simple design, which requires a minimum of effort on the part of the housewife in obtaining access to the clothes while safeguarding the clothes against removal except by an authorized person. Another object is to provide a guard providing sufficient space between itself and the door to allow several garments to hang therein, thus producing a safeguarded compartment. Yet another object is to provide a garment guard structure which does not interfere with vision through the door windows and which does not prevent the passage of light through the windows, while at the same time safeguarding clothes suspended upon the door against unauthorized removal. A still further object is to provide a structure which safeguards the clothes suspended upon the door against removal, while at the same time permitting ready access thereto by the housewife upon the opening of the door, lock means being provided for enabling an authorized person to obtain the clothes without opening the door. A still further object is to provide a guard structure in which a non-extensible or non-contractable gate may be employed, while at the same time providing locking means for retaining the gate in closed position when the door is closed but permitting opening of the gate when the door is opened. Still another object is to provide a

2

garment guard which is locked when the door is closed due simply to the juxtaposition of stationary parts, while at the same time permitting unlocking of the guard through the use of a key or other means independently of the opening of the door. Other specific objects and advantages will appear as the specification proceeds.

The invention is illustrated in preferred embodiments, by the accompanying drawings, in which—

Figure 1 is a front view in elevation of a door equipped with a structure embodying my invention; Fig. 2 is a broken, enlarged sectional view, the section being taken as indicated at line 15 2—2 of Fig. 1; Fig. 3, an enlarged detailed sectional view showing the locking structure; Fig. 4, a view similar to Fig. 3 but showing the door moved away from the door frame and the gate released from the locking bolt; Fig. 5, a side view 20 in elevation of a door equipped with a modified guard structure and showing a modified form of the invention; Fig. 6, an enlarged transverse sectional view, the section being taken as indicated at line 6—6 of Fig. 5; Fig. 7, a detailed sectional view showing the lock structure engaging the guard gate; Fig. 8, a view similar to Fig. 7 but showing the lock moved away from the gate to release the same; Fig. 9, a detailed sectional view, the section being taken as indicated at line 9—9 25 of Fig. 8; and Fig. 10, a perspective view of the lock casing and slide mounting therefor shown in detached relation.

In the structure shown in Figs. 1 to 4, inclusive, A designates a door and B a door frame surrounding the door.

35 The door A may be of any usual type of construction and may, if desired, be provided with windows 10. The door A may be provided, preferably near its upper end, with hooks or supports 11 upon which garment hangers may be suspended. In the illustration given, clothes hangers indicated by the numeral 12 and carrying garments or garments enclosed by bags may be employed. If desired, the loop portion of the hanger just below the hook may be inserted over the support 11 to further safeguard the clothes against removal.

40 The door A may be provided with a hinge structure 13 upon which is mounted the gate 14. The gate 14 may be provided with a rod frame 15 to which is secured angularly-extending wires 16. Since the form of gate is well known, a detailed description herein is believed to be unnecessary.

45 Mounted upon the side of the door opposite the hinges 13 is a lock 17 provided with a key-

controlled bolt 18. It will be understood that instead of employing a key-controlled lock, a combination or other form of lock, which may be manipulated only by authorized persons, may be employed. In the structure shown, the bolt 18 extends substantially to the adjacent portion of the door frame B, as shown more clearly in Fig. 3.

The gate frame 15 is provided at its free edge adjacent the lock 17 with a latch bar 19 having an inwardly-turned flange 20, the flange being apertured at 21 to receive the bolt 18. When the door is open, the latch bar 19, due to the slight play in the parts of the gate structure and to a slight resilience, may be drawn over the edge of the bolt 18 and the door swung to closed position, as shown in Fig. 3. In this position, the adjacent portion of the door frame B prevents the removal of the flange 20 from the bolt 18.

The gate 14 may be of any desired size, it being sufficient for the purposes of the present invention that the gate enclose the garments sufficiently to prevent their unauthorized removal. Further, instead of employing the specific rod and wire structure illustrated, it will be understood that other types of gates may be employed to accomplish the guard purpose described.

Operation

In the operation of the structure shown in Figs. 1 to 4, inclusive, the housewife, upon opening the door, may swing the gate 14 to an open position and may then suspend upon the hook or hooks 11 garments which are to be taken away by the pick-up man for the dry cleaners, and the like. The gate 14 may then be swung to closed position and drawn over the extended bolt 18, the resilience of the material moving the flange 20 to the position shown in Fig. 3. Upon the closing and the locking of the door, the garments are held securely against removal until the pick-up man arrives. The housewife may thus leave the building and will not be required to wait for the pick-up man. The authorized pick-up or deliveryman may, upon his arrival, insert a key into the lock 17 and withdraw the bolt 18 so as to free the flange 20 and latch bar 19. The gate 14 may then be opened although the door A remains in closed and locked condition. The garments may be removed and taken to the dry cleaning establishment, etc. The cleaned garments are later returned by the deliveryman and the hangers are placed upon the support or supports 11. With the door closed and locked, the deliveryman may turn the bolt 18 to the position shown in Fig. 3 to secure the gate 14 against being opened. The housewife, upon her return, by merely unlocking the door A and moving it away from the frame B, as shown in Fig. 4, can readily disengage the latch flange 20 from engagement with bolt 18. The resilience of the material permits this slight movement so that the flange 20 clears the bolt 18 and the gate 14 may be swung open to permit the housewife to remove the cleaned garments.

In the modification shown in Figs. 5 to 10, inclusive, the door A mounted within the door frame B is provided near its top with a hook or support 22 upon which a clothes hanger 23 may be suspended. Upon the hinged side of the door is secured a hinge 24 upon which is mounted a gate 25. The edges of the gate may be reinforced, if desired, by a rod 26 and wires 27 may be secured to the rod, as shown best in Figs. 5 and 6.

Upon the side of the door A opposite the hinges 24, I provide a lock 28, which is slideably mounted within a guide bracket 29. The guide bracket 29 is provided with openings 30 through 35 which screws may be extended to secure the bracket to the door, and the bracket is also provided with side walls 31 having inwardly-turned flanges 32, as shown more clearly in Fig. 10. One of the side walls 31 is preferably provided with an inwardly-turned stop lug 33, which may be formed by striking out a portion of the side wall 31 and forcing it inwardly, as shown more clearly in Figs. 9 and 10.

The lock 28 may be of the usual type of structure and is preferably provided with a laterally-extending flange 34 receivable below the flange 32 of the bracket 29. The lock 28 is provided with the usual key-controlled tumbler 35, which moves the locking bolt 36 to advanced or retracted positions. Since such a lock structure is of well-known design, a further detailed description is believed unnecessary. The side flange 34 on one side of the lock 28 is preferably cut away at 37 to provide stop shoulders 38, as shown best in Fig. 10.

The gate 25 is preferably turned inwardly at its edges and the locking bolt 36 extends over the rod 26, as shown best in Fig. 6, to latch the gate against being opened.

In the operation of the structure shown in Figs. 5 to 10, inclusive, the housewife, upon opening the door, may move the lock 28 to the right so as to cause the bolt 36 to clear the gate 25, as illustrated best in Fig. 8. The gate 25 may be opened and the garment hangers placed upon the hook 22. The gate may then be swung to closed position, as illustrated in Figs. 5 and 7, and the lock 28 may be slid inwardly to the position shown in Figs. 5 and 7. When the door A is closed, the gate 25 cannot be opened because the lock 28 is adjacent the door frame B and may not then be retracted. However, when the pick-up man arrives, he can insert his key within the lock 28 and retract the bolt 36 to free it from engagement with gate 25 even though the door A remains closed. Similarly, when he returns the cleaned garments, he can lock the gate 25 about the garments by extending the bolt 36 into engagement with the gate 25, as shown best in Figs. 5, 6 and 7. When the housewife returns, she may unlock the door and move it away from the door frame B, as shown in Fig. 8. Since the lock 28 is no longer obstructed by the door frame B, it may be moved outwardly away from the gate 25 and the gate thus released, as illustrated in Fig. 8. After removing the garments, the housewife may press the slideably mounted lock 28 inwardly to the position shown in Fig. 7 to again lock the gate in closed position. If desired, a tension spring may be attached to the lock 28 so as to normally maintain it in the locking position shown in Fig. 7.

While, in the foregoing specification, I have set forth specific structures in considerable detail for the purpose of illustrating embodiments of my invention, it will be understood that such details may be varied widely by those skilled in the art without departing from the spirit of my invention.

I claim:

1. In combination with a door mounted in a door frame with one side of said door hinged to said frame and with the frame adjacent the free side of said door extending laterally of said

door, a support for garments mounted upon the outside of said door, a gate mounted upon said door for movement into an enclosing position about said support and having a member at one end thereof adapted to be engaged for locking the gate member extensible toward the free side of said door, and a lock member mounted upon said door and equipped with a bolt movable laterally of the door and engageable with said member of said gate to lock the same in said enclosing position, one of said members being movable toward the free side of said door when said door is open to free said gate member from said bolt, said laterally-movable member, however, abutting the laterally-extending portion of said door frame adjacent the free end of said door when said door is closed, whereby lateral movement of said slideable member is prevented.

2. In combination with a door frame and a door therein hinged at one side to said frame, the free side of said door being of less width than the width of said frame, whereby said frame projects outwardly beyond the free side of said door, a garment support mounted upon the outside of said door, a gate mounted upon said door for movement into and away from an enclosing position about said support and having a member at one end thereof adapted to be engaged for locking the gate member extensible toward the free side of said door, and a lock member secured to the outside of said door and equipped with a slideable bolt member engageable with said member of said gate for locking said gate, one of said members being movable toward the free end of said door to effect disengagement of said bolt from said gate member when said door is open, said laterally-movable member of said door abutting the outwardly-projecting portion of said door frame when said door is closed, whereby movement of said laterally-movable member toward the free side of said door to effect disengagement of the gate member with said bolt is prevented while said door remains closed.

3. The structure of claim 2, in which the lock is a key-controlled lock.

4. The structure of claim 2, in which the laterally-movable member is the outer portion of the gate adjacent the free side of said door.

5. The structure of claim 2, in which the laterally-movable member is the lock which is slidably mounted upon said door.

6. In a garment guard adapted to be attached to the outer surface of a door, a gate hingeably mounted to the door at one side thereof, a support for garments carried by said door and adapted to be enclosed by said gate when the same is swung across the door, and a lock slideably mounted on said door and equipped with a bolt for locking said gate in said enclosing position, said lock being confined by the door frame to prevent opening of said gate when said door is closed but being slideable outwardly to release said gate from said bolt when said door is opened.

7. In a garment guard adapted to be secured upon the outer surface of a door, a support

mounted upon said door, a gate, means for supporting the gate for movement into an enclosing position about said support, and means, including a slideably mounted lock, for confining said gate in said enclosing position when said door is closed but slideable to release said gate when said door is open.

8. In a garment guard adapted to be supported upon a door, a gate hingeably mounted upon said door along one side thereof, a garment support mounted upon said door and adapted to be enclosed by said gate when said gate is swung across said door, a bracket mounted upon said door, a lock slideably held by said bracket, interlocking means on said lock and bracket for limiting the sliding movement of said lock, and a bolt carried by said lock for engaging said gate to lock the same in said support enclosing position, said lock being confined by the door frame when the door is closed to retain said bolt in locking engagement with said gate.

9. In a garment guard adapted to be supported upon a door, a gate hingeably mounted upon said door along one side thereof, a garment support mounted upon said door and adapted to be enclosed by said gate when said gate is swung across said door, a bracket mounted upon said door, a lock slideably held by said bracket, interlocking means on said lock and bracket for limiting the sliding movement of said lock, and a bolt carried by said lock for engaging said gate to lock the same in said support enclosing position, said lock being confined by the door frame when the door is closed to retain said bolt in locking engagement with said gate, said lock being provided with key controlled means for retracting said bolt to free said gate when the door is in closed position.

10. In combination with a door equipped with a support upon which garments may be suspended, a gate, means for mounting the gate along one side thereof to said door for swinging movement into enclosing position about said support, a bracket mounted upon said door at one side thereof adjacent the door frame and equipped with retaining flanges, a lock having side flanges slideably engaging the flanges of said bracket and provided with an inwardly-extending bolt, and key controlled means carried by said lock for retracting said bolt and for extending it into engagement with said gate to confine said gate in said enclosing position, said lock being restrained by the door frame when the door is in closed position to prevent release of said gate from said bolt, said lock being slideable to release said gate from said bolt when said door is opened.

LEO PETERS.
